SHEET-MANIPULATING MECHANISM FOR PRINTING-PRESSES.

1,175,807.

Specification of Letters Patent. Patented Mar. 14, 1916.

Application filed April 28, 1908; Serial No. 429,635. Renewed July 19, 1915. Serial No. 40,812.

To all whom it may concern:

Be it known that I, EDWARD L. JONES, a citizen of the United States, residing at Dover, in the county of Kent and State of Delaware, have invented certain new and useful Improvements in Sheet-Manipulating Mechanism for Printing-PresSES; and I do hereby declare the following to be a full, clear, and exact description of the invention, such as will enable others skilled in the art to which it appertains to make and use the same.

The general object of this invention is to improve the construction and increase the efficiency of operation of sheet-manipulating mechanism for sheet-printing presses, such as job-presses.

The invention has special reference to the means for separating the sheets as they are successively fed to the printing mechanism.

The invention will hereinafter be fully described by reference to the accompanying drawings, which form a part of this specification, and then more particularly pointed out in the claims at the end of this description.

It should be mentioned that the automatic sheet-feeder, which constitutes the principal subject-matter of this invention, is applicable to various types of printing-presses, but is illustrated herein applied to a rotary press which is also illustrated in my co-pending application filed April 28, 1908, Serial No. 429,636.

In said drawings: Figure 1 is a left-hand side elevation of a printing-press having my invention applied thereto. Fig. 2 is a right-hand side elevation thereof. Fig. 3 is a vertical section through the type and impression cylinders and automatic sheet-feeding apparatus. In this figure, the section through the feed-table is taken on line 3—3 of Fig. 5, while the section through the registering-table is taken on line 3—3 of Fig. 12, looking in the direction indicated by the arrows. Fig. 4 is an end view of the impression-cylinder. Fig. 5 is a top plan view of the automatic sheet-feeder. Fig. 6 is a perspective view of a part of the sheet-feeder, including the hopper for the package or pile of sheets, the paper-buffers, and the pneumatic sheet-separator. Fig. 7 is a vertical section of the sheet-separator, showing the smaller feed-rolls in elevation, and representing a sheet in the act of feeding.

Fig. 8 is a detail sectional view of the sheet-separator at starting position. Fig. 9 is a similar view at release position. Fig. 10 is a sectional view of the valve-connection between the suction-roller and suction-pump, 60 at the position corresponding to Fig. 8. Fig. 11 is a similar view at the position corresponding to Fig. 9. Fig. 12 is a plan view of the registering-table. Fig. 13 is a bottom plan view of half of the registering-table. 65

In the drawings, a rotary press-mechanism is shown mounted in an appropriate frame A constructed on a pedestal-base.

B denotes the type-cylinder on which is affixed the stereotype plate constituting the 70 printing form.

C denotes the impression-cylinder, provided with the usual tympan or blanket and with paper-grippers and shoofly.

D indicates the ink-fountain, and E the 75 distributing and composition rolls for inking the printing form.

F denotes as a whole the automatic sheet-feeding attachment which is the principal subject-matter of this invention, and by 80 means of which the sheets are successively separated, fed and presented in proper registration for taking by the grippers on the impression-cylinder.

G is a delivery-table upon which the 85 printed sheets are dropped when freed from the impression-cylinder, and H is an adjustable receiving table for collecting the finished sheets.

Motion is communicated from drive-shaft 90 1 having a pinion 2 (Fig. 2) meshing with gear 3 which in turn meshes with gear 4, whereby the type and impression cylinders are caused to revolve oppositely at the same speed. Pinion 2 also meshes with gear 5 95 on shaft 6 which through suitable connections operates the fountain-roll and ductor-roll of the inking-apparatus.

Power for running the press is applied by 100 a belt (not shown) adapted to be shifted by a controlling lever 7 (Fig. 1) carrying a belt shifter 8 for throwing the belt from a loose to a fast pulley 9 on shaft 1.

Referring to the impression-cylinder C, 105 whose surface is dressed with the proper tympan or blanket equipment, 10 indicates the grippers (Figs. 3 and 4) which close on the edge of the sheet presented to the cylinder and carry the sheet around in contact with the printing form; 11 is the gripper-rod and 110

12 the gripper-cam or tumbler which at each revolution is engaged by fixed pins or studs 13 and 14 for respectively opening and closing the grippers.

5 15 is the spring which holds the grippers either in open or closed position.

16 denotes the shoofly-fingers, 17 the shoo-fly-rod, and 18 a crank on one end of said rod, which when the grippers are opened 10 is struck by a fixed stud 19 for operating the shoofly to kick off or free the printed sheet from the impression-cylinder for delivery upon the conveying tapes of the delivery-table G.

15 As the inking-apparatus is commonly regarded as the front of a printing-press, corresponding relative terms will be employed in this specification. Accordingly the impression-cylinder may be considered as located 20 rearward of the type-cylinder, and the automatic sheet-feeder at the rear of the press above the delivery-table.

The automatic sheet-feeder F comprises a frame 20 supporting, preferably at a convenient incline, a reciprocating feed-table 21 and a stationary registering-table 22, the latter under the former. The reciprocating feed-table, operating in conjunction with a pneumatic sheet-separator, directs the sheets 30 successively to coacting feed-rolls 60, 61, 62 (Fig. 3), which feed them to the registering-table, from which the sheets are taken by the grippers of the impression-cylinder.

Feed-table 21, being adapted to reciprocate, is slidably supported by and between the upper side-bars of the frame 20, with coacting gibs and gib-ways, as shown more clearly in Fig. 5. Reciprocatory motion is imparted to said feed-table from cranks or 40 crank-wheels 23 on the shaft of the type-cylinder, connected by connecting-rods 24 with lateral arms 25 affixed to the table (Figs. 1, 2 and 5).

A hopper or receptacle for the pile of paper-sheets is provided on the feed-table by side-guides 26 and an end-gage 27, all of which are adjustably-secured by screw-clamps 28 fastened in slots 29 arranged cruciform in the feed-table (Figs. 3 and 5). 50 This permits the side-guides 26 to be adjusted laterally according to the width of the paper, while the end-gage 27 can be shifted back and forth to adjust the pile or package to proper position for separation by the pneumatic sheet-separator. The range of adjustability of the end-gage 27 is increased by a longitudinal slot in its base. The side-guides 26, consisting of elongated plates, extend beyond the front of the feed-table, since the paper pile also extends beyond and rests on the suction-roll of the pneumatic sheet-separator.

The pneumatic sheet-separator (Figs. 3 and 5 to 9) comprises a tubular or hollow 60 oscillating shaft or suction-roller 30, in

communication with a vacuum-pump and having a suction-orifice or aperture 31 for gripping the bottom sheet of the pile of paper, which, projecting beyond the front end of the feed-table, rests upon said shaft 70 and is carried back and forth thereover by reciprocations of said feed-table. Said shaft or suction-roller 30, journaled in the frame 20 in advance of the feed-table, is oscillated or rotated in opposite directions by a rack 32 attached to the feed-table and engaging a pinion 33 on said shaft (Figs. 2 and 5). As shown more clearly in Figs. 5 and 6, the central portion of the shaft, through which the aperture 31 is 80 drilled, is preferably slightly enlarged and is also longitudinally flattened in line with the aperture to present a flat surface for the bottom sheet and enable the air-suction to secure a perfect hold on the paper. This 85 flattened surface, in which the mouth of the aperture 31 is formed, comes approximately in the plane of the upper surface of the feed-table when the suction-aperture is turned back to raised position by the backward travel of the feed table (Fig. 3).

The variable space or gap between the feed-table and suction roller 30 is bridged at either side of the central boss of the shaft by flexible strips 34, preferably of canvas, which extend from the front edge of the feed-table in the plane thereof and are carried around and under the shaft 30 and fastened to retractile springs 35 which in turn are fastened to the under side of the 100 feed table, whereby said canvas strips are kept taut (Figs. 3, 5 and 6). These strips constitute a sort of extension of the feed-table to support the pile of sheets and prevent sagging between the feed-table and oscillating shaft 30.

In front of the suction-roller or shaft 30 is an inclined tongue 36 under which the bottom sheet is drawn by suction and over which the remainder of the pile rides at 110 each forward travel of the feed-table. See Figs. 3, 5, 7, 8 and 9. This tongue is provided with lateral wings or extensions 37, which are curved to overlie the suction-roller, and the edges of these wings are oppositely inclined or oblique with relation to the suction roller, the direction of obliquity being converging toward the suction-aperture 31. The tongue and wings as a whole 115 constitute a lip with oppositely-receding edges (Fig. 5). This prevents doubling up of the corners of the sheets, where the paper may have a tendency to curl, and avoids any interference with the perfect and regular feed; because, as the sheets are caught at the center by the suction-aperture 31 and carried under the lip or tongue, the front end of the sheet is drawn under the edges of the wings 37 progressively from the center toward opposite sides, and any curl or bend 120 125 130

in the corners of the papers is thus gradually eliminated. In other words, the converging oblique edges of the wings 37 have the effect, practically, of smoothing out the paper by passing progressively over the sheet from the middle toward its opposite sides.

The tongue 36 is shown hinged to a bracket 38 on an upper cross-bar mounted 10 on frame 20, and by means of a set-screw 39 (Fig. 7) the tongue can be adjusted according to the thickness or weight of paper to be fed. The tip of the tongue should lie slightly below the upper surface of the 15 suction-roller 30.

A vacuum or air-suction pump, which may be of any approved construction, is indicated by dotted lines in Fig. 2. The numeral 40 denotes the pump, whose piston 20 may be driven by a cam-crank or eccentric 41 on shaft 6. The pump-chamber is in communication through pipe or tube 42 with a cap 43 on a reduced end of the tubular suction-roller or oscillating shaft 30. As 25 shown in Figs. 10 and 11, the connection constitutes an oscillating valve. A port 44 in tube 30 registers alternately with two ports 45 and 46 in the case or cap, the former of which establishes communication with the 30 suction-pump while the latter establishes communication with the atmosphere. The ports 45 and 46 may therefore be respectively termed suction and release ports. At initial forward travel of the feed-table 21, 35 the port 44 registers first with the suction-port 45, whereby the suction-orifice 31 (Fig. 8) attracts the bottom sheet of the pile and separates it from its fellows by drawing it under the end of the tongue 36; and the port 44 then comes in registration with the release port 46, thus releasing the sheet from 40 the suction-orifice 31 (Fig. 9) and allowing the movement of the feed-table to direct the sheet to the feed-rolls 60, 61 (Fig. 7). On 45 return motion of the feed-table, the port 44 registers first with the release port 46, preventing the suction from interfering with the proper return of the pile of paper. The flange 47 of the cap 43 is shown having a 50 short segmental slot 48 through which is inserted a headed screw 49 which fastens the cap to the frame 20. By this fastening, the cap can be angularly-adjusted to regulate the time of registration of the ports 44 and 55 45 relative to the initial position of the suction-orifice 31.

At the discharge end of the hopper, buffers or stops 50 are provided to abut the front of the package or pile so as to prevent 60 the second sheet from following the first as well as to keep the pile in place (Figs. 3, 6 and 7). These buffers consist of arms depending from a rod 51 which is mounted to turn in openings in the side-guides 26. At 65 one side of the hopper, the rod 51 carries

an arm 52 on which acts a strong spring 53 whereby the buffers 50 are normally held in position to abut the front of the pile of paper. Said arm 52 is adapted to abut a stop or lug 54 on the outer face of the adjacent side guide to limit the position of the buffers 50 under action of spring 53. A bracket 55 on this same side-guide extends beside the head of the arm 52, which is thus embraced between the side-guide and said 70 bracket, whereby the rod 51 carrying the buffers is prevented from end-wise movement. The rod 51 also carries another depending arm 56 provided with a roller 57 at its lower end. When the feed-table moves 80 to its backward position, the roller 57 rides upon the shaft 30, thereby turning the rod 51 so as to rock the buffers 50 away from the front of the paper pile. On forward travel of the feed-table, by the time the bottom 85 sheet has been sucked under the tongue 36, the roller 57 leaves the shaft 30 and thus allows the buffers 50 to snap back into position to hold the paper pile; and it will be noted in Figs. 6 and 7 that the lower ends 90 of said buffers are formed with lips or small flanges 58 to catch under the pile from which the bottom-sheet is being separated. During the major reciprocation of the feed-table, while the roller 57 is off the shaft 30, the 95 buffers maintain a substantially constant pressure against the front of the pile, as distinguished from the spring-buffers or cushions heretofore used in connection with apparatus of this class and which are objectionable on account of the varying pressure which they exert with consequent liability to buckle the pile of paper. It will be noted that the rod 51 is longitudinally grooved and that the several arms carried 100 thereby are rigidly affixed by thumb screws 59 tapped through the heads of the arms and engaging in the groove of the rod.

In front of the oscillating suction-roller is the main feed-roll 60 and coacting smaller 110 rolls 61 and 62 arranged to receive the sheet which is separated and to feed it to the registering table 22 below (Figs. 2 and 7). The feed-roll 60, which drives its coacting rolls by contact, is driven from gear 4 through an idler 63 meshing with pinion 64 on the roll-shaft (Fig. 2). The rolls 61 and 62 are journaled in a frame 65 (Figs. 2 and 7) against which bears a spring 66 forcing said rolls in contact with the main 120 feed-roll 60. Said frame 65 is supported on a post 67 secured to and projecting from a cross-bar on the forward end of the feeder-frame 20.

A third roller 68 of relatively minute 125 diameter is placed below the feed-roll 62 and independently spring-held in contact with the main feed-roll 60; said minute roller 68 being journaled in spring-pressed arms 69 attached to the sides of the frame 65. The 130

purpose of this little roller 68 is to insure the timely delivery of the sheet of paper. As well understood the sheet which is being fed should drop upon the registering table 5 as soon as it is released from the feed-rolls. But in practice it is found that the end of the sheet will sometimes have a tendency to hang upon the last small roll, owing to the diameter of the latter, the roll providing a 10 sort of shelf beyond its point of contact with the main feed-roll. To overcome this difficulty, the minute roller 68 has been added as the last coacting feed-roll, from which the paper will readily drop off as 15 soon as it is released, as the radius of this roller 68 is too small to hang the sheet. The further function of the small roller 68 is to keep the paper high to avoid contact with the under sheet as it passes to the grippers. 20 Stripping-fingers 70, secured to a cross-rod 71 and projecting into peripheral grooves in the main feed-roll 60, strip the sheet from said feed-roll as it emerges from the minute roller 68. 25 Running rearward over the registering-table (Figs. 3 and 12) are endless tapes 72 for conveying the sheet to proper position for registry as it is fed from the feed rolls. These tapes run on rollers 73 and 74 on 30 shafts journaled at the opposite ends of the registering-table, and motion is communicated from the gear 4 which meshes with a pinion 75 on the shaft of the rollers 73. The bearings for the latter shaft are attached to the under side of the registering-table and the rollers 73 are arranged in 35 transverse openings in the table so that the upper surfaces of said rollers are substantially flush with the top of the registering-table. Said tapes 72 carry the sheet rearward under forwardly extending sheet-guides 76 and between lateral gages or sheet-guides 80 and 81. The sheet-guides 76 consist of forwardly-extending rods curved upward toward the feed-rolls to insure that the sheet will go down upon the lower table. Back gages 77, carried by adjusting-rod 78, are provided to limit the position to which the sheet is carried on the registering-table. 45 Said back-gages are shown formed to straddle the tapes 72 and the rods 76. Both sets of rods 76 and 78 are shown adjustably secured by set-screws in brackets 79 mounted on a cross-rod which is supported at the 50 rear of the registering-table. Both lateral gages or sheet-guides 80 and 81 are adjustably-secured by screw-clamps 82 engaging in cross-slots 83, for regulating the spacing according to the width of 55 the paper. One of said gages, in this case the left-hand gage 81, is adapted to vibrate and may be called a jogger, its function being to jog each sheet over to the right-hand gage 80 to effect the perfect registration on the sidewise adjustment of the sheet, 60

while the registration on the endwise adjustment is effected by proper positioning of the gages 77 in conjunction with the positive gripping of each sheet in exactly the same position by the grippers of the 70 impression-cylinder, as hereinafter explained. In view of the vibratory motion of the jogger or left-hand gage or sheet-guide 81, the slot for its adjusting clamp 82 is made in a 75 slide 84 working in a transverse way therefor in the registering-table. For vibrating the jogger, the slide 84 has a depending stud 85 engaged by the forked or bifurcated end of a spring-retracted lever 86 which is pivoted to the feeder-frame under the registering-table and has a short arm carrying a roller 87 which at each operation is engaged by a segmental cam 88 on one end of the impression-cylinder. An adjusting screw 89 limits the outward movement of the 85 slide 84.

The back-gages 77 on the registering-table are so adjusted that the front end of the sheet will extend slightly beyond the front end of the registering-table and rest 90 upon the surface of the impression-cylinder C. As soon as the sheet is brought to this position, the grippers close thereon and take the sheet from the registering-table and around with the impression-cylinder in contact with the printing-form on the type-cylinder, whereupon the grippers release and the shoofly kicks off the sheet, allowing air to get under it, and as it leaves the impression cylinder it passes on to the delivery table G and is carried by delivery-tapes 95 thereon to the receiving table H.

The operation may now be summarized as follows: Fig. 3 shows the machine at the beginning and also the completion of a cycle 105 of operations, for at the same time that a printed sheet is leaving the impression-cylinder the reciprocatory feed-table is ready to start the feed of another sheet, while still another sheet has been fed to the 110 registering-table. By means of end-gage 27 of the hopper, the pile of sheets is adjusted on the feed-table so that the front end of the pile will rest over the suction-aperture 31 of the suction-roller 30, the said aperture 115 having been brought to raised position by the backward travel of the feed-table. During one rotation of the impression-cylinder, the feed-table makes a complete reciprocation. As the feed-table moves forward, the 120 suction-roller 30, through port 44 registering with suction-port 45 (Fig. 10), is in communication with the vacuum-pump 40, thereby creating suction at the aperture 31 which attracts the bottom sheet of the pile 125 and holds it down until the front edge of the sheet has passed under the tongue 36 (Fig. 9), the remaining bulk of the pile riding over said tongue; whereupon the release port 46 comes into registration with 130

port 44 and releases the sheet (Fig. 11). The bottom sheet being thus separated is directed by the forward travel of the feed-table to the coating feed rollers 60, 61 (Fig. 7) which grip it and carry it around between rolls 60, 62 and 60, 68 to the registering-table (Fig. 3), where the tapes carry it back to the gages 77; meanwhile the feed-table 21 returns to its original position, the pile of paper being carried back therewith and maintained in place by the buffers 50. This completes the first revolution of the impression-cylinder. During the second revolution (while a second sheet is being fed in like manner) the cam 88 on the end of the impression-cylinder (Figs. 4 and 13) passes the friction-roller 87 on the jogger, thereby operating the spring-retracted lever 86, which moves the jogger 81 inward and jogs the sheet over to the left-hand guide or gage 80, giving the uniform register on the side-wise adjustment of the sheet. The grippers 10 of the impression-cylinder, operated by the closing-pin 14 engaging the gripper-cam, now close upon the top edge of the sheet and draw it off the registering-table and around in contact with the printing-form; while at the same time the second sheet is being fed down upon the registering-table. The first sheet, having been carried in contact with the type, is released by opening of the grippers, actuated by the opening-pin 13 engaging the gripper-cam, and immediately the shoofly 16 is operated by the pin 19, thus kicking off the sheet and allowing it to drop upon the delivery tapes of the table G. At the time the grippers open to release the printed sheet, the second sheet has been fed to the back-gages 77 on the registering-table, ready to be jogged over to the left-hand gage 80, and a third sheet is just ready to be fed by the feed-table.

As previously stated, perfect registration of the sheet depends not only upon the action of the jogger 81 and adjustment of the back gages 77, but also upon the grippers closing on the edge of each sheet at exactly the same point. For this purpose the grippers are positively operated by engagement of the pins 13 and 14 in a relatively long slot in the gripper cam or tumbler 12, and the spring 15 is depended upon only to hold the grippers opened or closed. This causes the closing-stud 14 to leave the cam only when the grippers close on the sheet, and consequently they close always at the same point. It has been found in practice that when the gripper-cam is made with the ordinary shorter slot, variations in speed of the press would cause the grippers to close at different points, sometimes taking a one-fourth inch bite on the sheet and sometimes as much as a three-eights inch bite, thus impairing the register. This difficulty is ob-

viated by the longer slot in the gripper-cam, and the positive operation of the grippers as pointed out.

It is noted that the front portion of the automatic feeder attachment overlies the impression-cylinder, and would therefore obstruct access to the impression-cylinder for dressing its surface or applying the tympan. For this reason, the front of the frame 20 is constructed at 90 in the form of a right angle, fitting upon correspondingly shaped corners of the sides of the frame A, and the vertical legs of the angled portions 90 are hinged at 91 to the rear of the frame A, while the horizontal legs are secured to the top of the main frame by bolts 92. On loosening the fastening nuts of the bolts 92, the feeder attachment can be swung rearward and off the impression-cylinder. The connecting rods 24 are hooked over grooved collars on the arms 25 on the feed-table to permit convenient disconnection when the automatic feeder is to be swung off the impression-cylinder.

The press herein selected for illustrating the invention is equipped with an automatic throw-off mechanism for separating the impression-cylinder from the type-cylinder when no sheet has been fed or taken by the grippers, but when the type-cylinder and impression-cylinder are separated by the operation of the throw-off mechanism these cylinders continue to rotate and the operation of the throw-out does not affect the rotation of the impression-cylinder and the type-cylinder. This throw-off mechanism constitutes the subject-matter of my aforesaid application Serial No. 429,636, and hence need not be described herein. The throw-off of the impression-cylinder, and accompanying shift of the gear 4, necessitates a slight shift of the gear 75 which drives the conveying tapes on the registering-table, and for this purpose the registering-table is adapted for sliding adjustment, the pinion 75 being maintained in mesh with the gear 4 but shifting therewith.

Having thus described my invention, what I claim as new and desire to secure by Letters Patent of the United States is:

1. In an automatic sheet-feeder, the combination of a reciprocatory feed-table, a rotative sheet-separating suction-roller over which a pile of sheets is reciprocated by said feed-table, a hopper for the pile of sheets arranged on said feed-table and having its side-members forwardly-extending beyond the same, a rod transversely-mounted in the forward portions of said side-members and carrying one or more depending buffer-arms for the forward end of the pile, a spring secured to the side of the hopper and to said rod and acting on said rod to maintain it in normal position, and an arm on said rod provided with a roller

which, on completion and beginning of each reciprocation, rides upon said suction-roller and thereby displaces said buffer-arms.

2. In a device of the character stated, a reciprocatory feed table for holding a pile of sheets, an oscillating suction roller having a suction opening formed therein and provided with a flattened portion around the said suction opening, in order to provide 5 a flat bearing surface for the sheet, when held thereagainst, a tongue projecting to a point adjacent said suction roller, a feed roll situated beneath said tongue and spaced from said suction roller and over which the 10 sheet is fed from said suction roll, said suction roll and feed roll being mounted to retain their same relative positions at all times with the upper surface of said roll in a horizontal plane above the upper surface of 15 said suction roller, and coöperating feed rolls suitably mounted adjacent said first mentioned feed roll.

3. In a device of the character stated, a reciprocatory feed table, a rotative sheet 25 separating suction roll, a tongue projecting to a point adjacent said suction roll and having lateral wings upon each side, which are oppositely inclined or oblique with relation to the suction roll and extend downwardly, a feed roll situated beneath said tongue and spaced from said suction roll and over which the sheet is fed from the suction roll, and coöperating feed rolls adjacent said first mentioned feed roll.

- 35 4. In an automatic sheet feeder, the combination of a reciprocatory feed table, a rotative sheet separating suction roll over which a pile of sheets is reciprocated by said feed table, a rod transversely mounted 40 in the forward portion of said feed table and carrying one or more depending buffer arms for the forward end of the pile of sheets carried by said table, means for maintaining said rod in its normal position, and 45 means, which on the completion of each reciprocation of the feed table, rides upon said suction roll and thereby rocks said buffer arms.

5. In an automatic sheet feeder, a reciprocatory feed table having an open-ended hopper for a pile of sheets, a coöperative sheet-separator, an abutment for the forward end of the pile located at the open or discharge end of the hopper and carried by the feed 55 table, and automatic means at one side of the hopper and adapted for direct engage-

ment with said sheet separator on the completion of each reciprocation of the feed table for displacing said abutment during attraction of the sheet which is being separated. 60

6. In an automatic sheet feeder, a reciprocatory feed table having an open-ended hopper for a pile of sheets, a coöperative sheet-separator, a rod mounted transversely 65 in the forward open end of said hopper, one or more depending buffer-arms carried by said rod, and means at one side of the hopper and adapted for direct engagement with said sheet separator on the completion of 70 each reciprocation of the feed table for maintaining said rod in position and for turning it to displace the buffer-arms during attraction of the sheet by the sheet-separator. 75

7. In an automatic sheet feeder, a reciprocatory feed table having an open-ended hopper for a pile of sheets, a coöperative sheet-separator, a rod mounted transversely 80 in the forward open end of said hopper, one or more depending buffer-arms carried by said rod, and means at one side of the hopper and adapted for direct engagement with said sheet-separator on the completion of 85 each reciprocation of the feed table for maintaining said rod in position and for turning it to displace the buffer-arms during attraction of the sheet by the sheet-separator, said arm or arms having bottom lips or flanges to catch under the bottom of the 90 pile. 95

8. In apparatus of the character stated, a feed-roller around which sheets of paper can pass, means for rotating such roller, a frame supported to be slidable toward and 100 from said roller, springs bearing against said frame to force it against said feed-roller, rollers journaled in said frame to bear against said feed-roller, arms extending to a point beneath said feed roller and pivotally mounted upon said frame to move therewith and to have movement independently thereof, a small-diameter roller journaled in said arms, and springs bearing against said arms to force them and said 105 roller against the feed-roller.

In testimony whereof I affix my signature, in presence of two witnesses.

EDWARD L. JONES.
